United States Patent Office

Des. 203,843
Patented Feb. 22, 1966

203,843

TOY VEHICLE

Laurie J. Campbell, Erie, Pa., assignor to Louis Marx & Co., Inc., New York, N.Y., a corporation of New York

Filed June 18, 1965, Ser. No. 85,803

Term of patent 14 years

(Cl. D34—15)

FIG. 1

FIG. 1 is a top plan view of a toy vehicle embodying my new design;

FIG. 2 is a side elevational view thereof;

FIG. 3 is a view similar to FIG. 2 showing the opposite side;

FIG. 4 is a front end view thereof; and

FIG. 5 is a rear end view thereof.

The dominant features of my design reside in the portions shown in full lines.

I claim:

The ornamental design for a toy vehicle, as shown and described.
